(57) **CLAIM**

The ornamental design for a mobile convertible bench, as shown and described.

DESCRIPTION

FIG. 1 is a front perspective view of a mobile convertible bench in a table configuration depicting the new design; FIG. 2 is a front elevation view of the mobile convertible bench depicted in FIG. 1;

FIG. 3 is a rear elevation view of the mobile convertible bench depicted in FIG. 1;

FIG. 4 is a top plan view of the mobile convertible bench depicted in FIG. 1;

FIG. 5 is a bottom plan view of the mobile convertible bench depicted in FIG. 1;

FIG. 6 is a left side elevation view of the mobile convertible bench depicted in FIG. 1;

FIG. 7 is a right side elevation view of the mobile convertible bench depicted in FIG. 1;

FIG. 8 is a left side elevation view of the mobile convertible bench depicted in FIG. 1, in a bench configuration.

FIG. 9 is a left side elevation view of the mobile convertible bench depicted in FIG. 1, in a storage configuration.

FIG. 10 is a rear perspective view of the mobile convertible bench depicted in FIG. 1, in a bench configuration; and,

FIG. 11 is a front perspective view of the mobile convertible bench depicted in FIG. 1, in a bench configuration.

Any broken lines showing in the drawings are for illustrative purposes only and form no part of the claimed design.
